United States Patent Office

Des. 185,624
Patented July 7, 1959

185,624

TEXTILE FABRIC

Sidney E. Blumenthal, New Orleans, La., assignor to Blumenthal Print Works, Inc., New Orleans, La., a corporation of Louisiana

Application December 23, 1957, Serial No. 48,993

Term of patent 7 years

(Cl. D92—1)

The figure is a plan view of a textile fabric showing my new design, the full width is shown vertically and the design is repeated horizontally.

I claim:

The ornamental design for a textile fabric, as shown.
